United States Patent Office.

JOHN HOARE, OF NEW YORK, N. Y.

Design No. 4,752, dated April 4, 1871.

DESIGN FOR A CASTER-BOTTLE.

The Schedule referred to in these Letters Patent and making part of the same.

To all whom it may concern:

Be it known that I, JOHN HOARE, of the city, county, and State of New York, have invented a new and original Design for Caster-Bottles; and I do hereby declare that the following is a full, clear, and exact description thereof, which will enable others skilled in the art to make and use the same, reference being had to the accompanying drawing forming part of this specification, in which—

Figure 1 represents my improved design as applied to a vinegar-cruet.

Figure 2 represents my improved design as applied to a pepper-box or bottle.

Figure 3 represents my improved design as applied to a mustard-cup or bottle.

Similar letters of reference indicate corresponding parts.

My invention has for its object to furnish an improved design for caster-bottles; and

It consists in the design hereinafter more fully described.

A are the lower parts of the bottles, which enter the frame of the caster or stand, and which are made cylindrical in form, in the ordinary manner.

The upper part B of the bottles is made in a conical

form, as shown in figs. 1, 2, and 3, that is to say; it tapers gradually from the swell or shoulder at the upper end of the cylindrical lower part A to the neck of the bottle.

The form of the neck C of the bottle must depend upon the character of the substance which the bottle is to contain; that is to say, whether it be a liquid to be poured, a powder to be sprinkled or dusted, or a semi-fluid to be removed with a spoon.

The conical part B of the bottle, to which my design especially relates, may be cut or engraved, or cut in part and engraved in part, as may be desired; or it may be ornamented in other ways, as may be desired, or as the taste of the maker may dictate, the ornamentation forming no part of my improved design.

I claim—

The design for caster-bottles herein shown and described.

The above specification of my invention signed by me this 2d day of February, 1871.

JOHN HOARE.
